UNITED STATES PATENT OFFICE.

OTTO CARL SCHROEDER, OF DETROIT, MICHIGAN.

EYE-CLEANER.

1,263,942.

Specification of Letters Patent. Patented Apr. 23, 1918.

Application filed May 10, 1917. Serial No. 167,790.

To all whom it may concern:

Be it known that I, OTTO C. SCHROEDER, a citizen of the United States, residing at Detroit, in the county of Wayne and State of Michigan, have invented certain new and useful Improvements in Eye-Cleaners; and I do declare the following to be a full, clear, and exact description of the invention, such as will enable others skilled in the art to 10 which it appertains to make and use the same.

This invention relates generally to medical appliances, and more particularly to new and useful improvements in eye cleaners.

15 The primary object of the invention is to provide an instrument by which extraneous matter such as dust and dirt may be removed from the human eye without injury to the eye or annoyance to the person.

20 Another object of the invention is to generally improve upon devices of this class by the provision of an extremely simple, strong, durable and inexpensive construction, one which will be efficient and reliable in operation, and well adapted to the purpose for which it is designed.

With these and other objects in view, the invention consists of certain novel features of construction, and the combination and arrangement of parts which will be hereinafter 30 fully described and claimed.

In the accompanying drawing forming a part of the application:

Figure 1 is a longitudinal sectional view 35 of a device constructed in accordance with this invention;

Fig. 2 is a side view thereof;

Fig. 3 is a top view of the same;

40 Figs. 4 and 5 are transverse sectional views taken on the planes indicated by the lines 4-4 and 5-5 respectively of Fig. 1; and

Fig. 6 is an elevation of the casing.

Referring more particularly to the drawing, the numeral 1 designates a handle having a threaded portion 2 and a ring 3 by which the device may be connected to a watch chain or the like. Fixed to the handle 1 and projecting longitudinally of the same 50 is a cleaning bar or element 5 having a core or spine 4 extending centrally through the same. The spine 4 is formed of resilient metal, while the member 5 is formed of a resilient and flexible substance, preferably

of rubber, and is tapered from its inner 55 toward its outer end. The edges of the member 5 are grooved as at 6, and one side 7 of said member is convex while the other side 8 is concave.

While it is desirable to use the spine 4 as a 60 stiffener, yet it is to be understood that this may be entirely omitted without departing from the principle of the invention.

A casing 9 of any suitable material may be used to inclose the cleaner, this casing being 65 provided with a retracted mouth adapted to receive the threads 2 of the handle 1.

In using a device constructed as above described, the sides and edges of the member 5 are moistened in any suitable manner, but 70 preferably by placing it in the user's mouth for a moment, and then drawing the eyelid back and passing it back and forth across the eye, the resiliency of the various parts of the member allowing it to bend to conform 75 to the shape or surface of the eye. The member 5 is always held in such relation to the eye so that its concaved side 8 will contact with the surface of the same. The saliva or other moisture on the surface of the member 80 5 will cause the particles of dust or other extraneous matter to adhere to the latter and be collected in the grooves in the edges of the member as it is passed over the eye. The rubber from which the cleaning member 5 85 is made having smooth surfaces will not injure the eye in any manner whatsoever.

From the foregoing description, taken in connection with the accompanying drawing, the construction and use of the invention 90 will be readily understood without a more extended explanation.

As various changes in form, proportion and in the minor details of construction may be resorted to without departing from the 95 spirit of this invention, it is to be understood that I do not wish to limit myself to the precise construction herein shown and described.

I claim:

1. An eye-cleaner adapted to be inserted and moved transversely between the eyelid and the eyeball, said cleaner comprising a relatively flat tapered stem of flexible nature to permit it to curve longitudinally around 105 the eye ball, one side of said stem being concave throughout its length for free movement over the ball without injuring the

same, and the opposite side of said stem being convex throughout its length for similar engagement with the eyelid.

2. An eye cleaner adapted to be inserted and moved transversely between the eyelid and the eyeball, said cleaner comprising a relatively flat tapered stem of flexible nature to permit it to curve longitudinally around the eye ball, one side of said stem being concave throughout its length for free movement over the ball without injuring the same, and the opposite side of said stem being convex throughout its length for similar engagement with the eyelid, the edges of

the stem each having a longitudinal groove 15 whose sides are located substantially at the corners of said stem, said grooves extending throughout the length of the stem and being adapted to collect extraneous matter between the eyeball and eyelid. 20

In testimony whereof I have hereunto set my hand in the presence of two subscribing witnesses.

OTTO CARL SCHROEDER.
